(57) **CLAIM**

The ornamental design for a bicycle rack, as shown and described.

DESCRIPTION

In a preferred embodiment, the nature of this product is as an structure primarily useful for supporting parked bicycles. FIG. 1 is a left, top, front perspective view of a bicycle rack embodying our new design;

FIG. 2 is a front elevational view thereof, the rear elevational view being identical to the front elevational view shown; FIG. 3 is a top plan view thereof;

FIG. 4 is a bottom plan view thereof;

FIG. 5 is a left side elevational view thereof, the right side elevational view being identical to the left side shown; FIG. 6 is a front elevational view of a base of the bicycle rack with reference lines indicating locations of cross sectional views of subsequent figures;

FIG. 7 is a cross-section view along line 7—7 in FIG. 6; FIG. 8 is a cross-section view along line 8—8 in FIG. 6; FIG. 9 is a cross-section view along line 9—9 in FIG. 6;

FIG. 10 is a cross-section view along line 10—10 in FIG. 6; FIG. 11 is a cross-section view taken longitudinally through the center of the base of the bicycle rack; and, FIG. 12 is a front elevational view of second embodiment of the bicycle rack embodying our new design, the rear elevational view being identical to the front elevational view shown, a top plan view thereof being identical to FIG. 3, a bottom plan view being identical to FIG. 4, and a left side elevational view thereof and a right side elevational view thereof both being identical to FIG. 5.
